PLATE HANGER

Charles Richards, Quincy, Mass.

Application December 24, 1942, Serial No. 470,010

11 Claims. (Cl. 248—30)

This invention relates to a plate hanger designed for attachment to a plate for wall decoration and display.

The object of the invention is to provide a novel and improved plate hanger for the purpose specified which may be economically manufactured, is of a simple and durable structure, and which may be used with advantage to support plates of varying sizes, shapes and configurations upon a wall for display and decorative purposes.

With this general object in view, and such others as may hereinafter appear, the invention consists in the plate hanger hereinafter described and particularly defined in the claims at the end of this specification.

In the drawing illustrating the preferred embodiment of the invention, Fig. 1 is a front view of my improved plate hanger; Fig. 2 is a side elevation thereof; Fig. 3 is an enlarged detail view, partly in cross-section, of locking mechanism embodied in the illustrated plate hanger, shown in its unlocked position; Fig. 4 is a similar view showing the mechanism in its locked position; Figs. 5 and 6 are cross-sectional views taken on the lines 5—5 and 6—6 of Figs. 3 and 4 respectively; and Figs. 7 and 8 are detail views in side elevation, partly in cross-section, of a modified form of locking device shown in unlocked and locked positions respectively.

In general, the present invention contemplates a plate hanger of flexible material, such as thin metal or a plastic material, and the hanger consists essentially of two elongated supporting members slidably connected together and adapted to be adjusted to the plate to be supported. One member comprising the main supporting member has provision at its upper end for attachment to the wall and is provided at its lower extremity with one or more forwardly extending hooked portions adapted to hook over the lower portion of the rim of the plate to be displayed. The second elongated member comprises a bar which is formed straight for a major portion of its length and provided with a hooked portion at its upper end and adapted to hook over the upper portion of the plate. The two supporting members may be held in assembled relation by one or more loops or collars embracing the parts and provision is made for frictionally locking the parts in their adjusted position in a simple and efficient manner.

A feature of the present invention resides in the structure of the plate hanger whereby when in use none of the parts of the hanger are visible from the front except the relatively small rim

engaging portions when used for supporting a plate within the limits for which the hanger is designed. The present construction of hanger is also capable of adjustment to fit a relatively wide range of sizes of plates.

Referring now to the drawing which illustrates the preferred embodiment of the invention, 10 represents the main supporting member comprising a flexible but relatively stiff metal or plastic strip having its lower end portion provided with diverging and forwardly extended plate supporting hook members 12 which are adapted to hook over the lower portion of the periphery of the plate 15 when the supporting member 10 is disposed vertically along the under or rear surface of the plate, as shown in Figs. 1 and 2. The second supporting member 16 comprises an elongated adjustable clamping member which is straight for a major portion of its length and is provided with a forwardly extended hooked portion 18 at its upper end for cooperation with the upper portion of the plate.

The supporting member 10 is provided with a hole 20 at its upper end through which a nail or other fastening device 22 may be driven to attach the plate hanger to a wall 24, and as illustrated in Figs. 1 and 2, the upper or fastening end of the main supporting member 10 is preferably designed to be of such a length as to come within the circumference of the plate 15, being supported so as to be concealed by the latter when in use. The upper or fastening end of the main supporting member 10 is also preferably offset, as indicated at 26, in order to provide a handle to be grasped when tightening the device about a plate, as will be described and also to provide a clearance space between the wall and the plate for the head of the fastening device 22. The offset structure of the upper portion of the member 10 is also advantageous in effecting a slight angular disposition of the plate against the wall, as illustrated, so that the plate is tilted slightly forward to more readily reveal its decorative features when placed in a relatively high position on the wall.

In order to hold the supporting members 10 and 16 in assembled relation, one or more loops or collars 28, 30 may be provided which are arranged to embrace the parts as shown to permit longitudinal adjustment of one supporting member with relation to the other. In the embodiment of the invention, as illustrated in Figs. 1 to 6, the spaced collars 28, 30 may and preferably will be fixed to the main supporting member 10 at points 32, 34, the collars 28, 30 providing suf-

ficient clearance 36 to permit free sliding movement of the member 16. In order to lock the parts together in their adjusted position a laterally movable wedge shaped member 38 is provided intermediate the collars 28 and 30 which is arranged to be received between the two members 10 and 16, and which may be supported in an offset portion 40 of the main supporting member 10. The wedge shaped member 38 may be provided with end stops 42 in order to prevent complete withdrawal thereof, and in operation, as illustrated in Figs. 3 and 5, when the wedge is pushed in one direction, sufficient clearance is provided to permit the members 10, 16 to be moved longitudinally with relation to each other. When the wedge is moved in the opposite direction, as shown in Figs. 4 and 6, the wider portion of the wedge effects a yielding separation of the flexible members 10, 16 to bind the parts at the points 43, 44 adjacent the collars 28, 30 and thus lock the parts securely together. In order to prevent the parts from slipping apart and to further assure positive locking of the parts, the contacting faces of the members 16 and 38 may and preferably will be provided with serrated, grooved or otherwise roughened surfaces, as indicated at 45 in Figs. 3 and 4. The wedge shaped member 38 may and preferably will be proportioned so as to effect locking when the member is disposed in a central position as shown in Fig. 6.

From the description thus far it will be observed that when assembling the hanger upon a plate the lower hook members 12 are hooked over the lower portion of the rim of the plate and then the slideable member 16 is manually moved into position to engage the upper portion of the rim of the plate while the wedge shaped member 38 is moved to the left, as shown in Fig. 5. The offset portion 26 of the main supporting member 10 may then be grasped and held while the member 16 is firmly placed in plate engaging position either by pressing down on top of the hooked portion 18 or by pulling on the lower extended end of the member 16 thus pulling the members 10, 16 in opposite directions to grasp the plate tightly. Thereafter, the wedge shaped member 38 is pushed into binding position to hold the parts securely locked together.

Referring again to Fig. 1, and assuming for purposes of explanation that the plate therein shown in dotted lines is the minimum size of plate for which the present hanger is designed, it will be observed that the elongated member 16 extends downwardly a substantial distance to permit upward adjustment to take care of a relatively wide range of sizes, and yet the part 16 is at all times entirely concealed behind the plate when in use. Although the illustrated hanger may be adjusted to take care of a smaller size of plate than shown, such adjustment would reveal both the attaching end of the member 10 and the lower end of the member 16, so that in practice it is preferred to use a different size of hanger proportioned to accommodate smaller sizes of plates. In practice, but three sizes of hangers are required to accommodate practically any size plate now commercially used. In order to prevent complete withdrawal of the member 16 from the assembled unit, a stop member 46 may be provided at the extended end of the member 16, as shown, for engagement with a portion of the main supporting member 10 when the member 16 is adjusted upwardly to its maximum extent.

As a modification of the above described embodiment of the invention, the loops or collars 28,

30 may be loosely mounted to be movable upon the parts 10, 16, so that in operation movement of the collars toward the inserted member 38 will effect binding and locking of the parts together. In the latter event the member 38 need not necessarily be wedge shaped, but may comprise an insert of uniform cross section interposed between the parts 10 and 16, the locking action being effected by the flexing of the parts under the influence of the collars 28, 30 forced towards the interposed member.

Referring now to Figs. 7 and 8, another modification of the locking means embodied in the present plate hanger may comprise a longitudinal wedge shaped member 50 formed integrally with or attached to the upper portion of the main supporting member 10, as illustrated, and a single loop or collar 52 loosely embracing and movable upon the members 10 and 16. With this construction it will be seen that when the collar 52 is moved to a lowered position, as shown in Fig. 7, the parts may be easily adjusted longitudinally with relation to each other, and when the collar is moved upwardly, it will effect binding of the parts 10 and 16 against the wedge shaped portion 50, as clearly shown in Fig. 8. The contacting surfaces may also be roughened, as shown, to provide efficient gripping areas. Since but one collar 52 is employed, side guides 54, 56 may be provided adjacent the top of the wedge portion to maintain the member 16 in vertical alignment with the member 10.

A further modification embodying a longitudinal wedge may comprise a reversal of the wedge shaped member shown in Fig. 8 so that the small end of the wedge is uppermost. The collar 52 would then be disposed at the top of the wedge, and in order to retain the members 10 and 16 in alignment a fixed collar may be provided below the wedge. The latter construction eliminates the possibility of the collar 52 becoming inadvertently loosened and disengaged from its locking position.

From the above description it will be observed that the present construction of plate hanger may be economically manufactured, is capable of adjustment to accommodate a wide range of sizes of plates, and that the hanger is practically entirely concealed behind the plate being supported when in use. It will also be observed that the present structure of plate hanger enables the parts to be securely locked in their adjusted positions on the plate in a simple, practical and convenient manner. Although the structure lends itself for manufacture from relatively thin strips of metal, such as brass, when such materials are unavailable it has been found in practice that hangers made from any of the commercially available plastic materials are extremely serviceable.

While the preferred embodiment of the invention has been herein illustrated and described, it will be understood that the invention may be embodied in other forms within the scope of the following claims.

Having thus described the invention, what is claimed is:

1. A plate hanger for attachment to a plate for wall decoration and display, comprising a main supporting member of relatively thin flexible material having provision at its upper end for attachment to the wall and provided at its lower end with forwardly extended, diverging hook portions for engagement with the lower rim portion of the plate, an elongated supporting member

having a forwardly extended hook portion at its upper end for engagement with the upper rim portion of the plate, encircling means for retaining the members in assembled relation and to permit longitudinal adjustment of said elongated member, one of said members having a raised portion on one face thereof for cooperation with said encircling means arranged to flex said members to effect frictional locking of the parts in their adjusted position.

2. A plate hanger for attachment to a plate for wall decoration and display comprising a main supporting member having provision at its upper end for attachment to the wall and provided at its lower end with forwardly extended, diverging hook portions for engagement with the lower rim portion of the plate, an elongated supporting member having a forwardly extended hook portion at its upper end for engagement with the upper rim portion of the plate, means for retaining the members in assembled relation and to permit longitudinal adjustment of said elongated member, and means including a wedge shaped member interposed between said supporting members for locking the parts in their adjusted position.

3. A plate hanger for attachment to a plate for wall decoration and display comprising a main supporting member of relatively thin flexible material having provision at its upper end for attachment to the wall and provided at its lower end with forwardly extended, diverging hook portions for engagement with the lower rim portion of the plate, an elongated supporting member having a forwardly extended hook portion at its upper end for engagement with the upper rim portion of the plate, a movable collar embracing the members for retaining them in assembled relation, and a wedge-shaped member interposed between said supporting members adapted to permit longitudinal adjustment of the parts when the collar is moved away from the interposed member and arranged to flex said supporting members to bind the parts together in locked relationship when the collar is moved toward the interposed member.

4. A plate hanger for attachment to a plate for wall decoration and display comprising a main supporting member having provision at its upper end for attachment to the wall and provided at its lower end with forwardly extended, diverging hook portions for engagement with the lower rim portion of the plate, an elongated supporting member having a forwardly extended hook portion at its upper end for engagement with the upper rim portion of the plate, a pair of spaced collars embracing said members and fixedly attached to the main supporting member, and a laterally movable wedge interposed between said supporting members intermediate said spaced collars and operative to permit said supporting members to be longitudinally adjusted when said wedge is moved in one direction and to flex the members into binding relationship with said collars when moved in an opposite direction to lock the parts in their adjusted position.

5. A plate hanger for attachment to a plate for wall decoration and display comprising a main supporting member having provision at its upper end for attachment to the wall and provided at its lower end with forwardly extended, diverging hook portions for engagement with the lower rim portion of the plate, an elongated supporting member having a forwardly extended hook portion at its upper end for engagement with the

upper rim portion of the plate, a collar loosely embracing said supporting members, and a longitudinally disposed wedge interposed between said supporting members adapted to permit longitudinal adjustment of the parts when the collar is moved away from the wedge and to lock the parts in their adjusted position when the collar is moved toward the wedge.

6. A plate hanger for attachment to a plate for wall decoration and display comprising a main supporting member having provision at its upper end for attachment to the wall and provided at its lower end with forwardly extended, diverging hook portions for engagement with the lower rim portion of the plate, an elongated supporting member having a forwardly extended hook portion at its upper end for engagement with the upper rim portion of the plate, a pair of spaced collars embracing said members and fixedly attached to the main supporting member, and a laterally movable wedge interposed between said supporting members intermediate said spaced collars and operative to permit said supporting members to be longitudinally adjusted when said wedge is moved in one direction and to flex the members into binding relationship with said collars when moved in an opposite direction to lock the parts in their adjusted position, said laterally movable wedge being provided with stop lugs at either end to prevent complete withdrawal thereof.

7. A plate hanger for attachment to a plate for wall decoration and display comprising a main supporting member having provision at its upper end for attachment to the wall and provided at its lower end with forwardly extended, diverging hook portions for engagement with the lower rim portion of the plate; an elongated supporting member having a forwardly extended hook portion at its upper end for engagement with the upper rim portion of the plate, a collar loosely embracing said supporting members, said main supporting member having a longitudinally disposed wedge on its inner face arranged to cooperate with said collar whereby to permit longitudinal adjustment of the parts when the collar is moved away from the wedge and to lock the parts in their adjusted position when the collar is moved toward the wedge.

8. A plate hanger for attachment to a plate for wall decoration and display comprising a main supporting member having provision at its upper end for attachment to the wall and provided at its lower end with forwardly extended, diverging hook portions for engagement with the lower rim portion of the plate, an elongated supporting member having a forwardly extended hook portion at its upper end for engagement with the upper rim portion of the plate, a collar loosely embracing said supporting members, and a longitudinally disposed wedge interposed between said supporting members whereby to permit longitudinal adjustment of the parts when the collar is moved away from the wedge and to lock the parts in their adjusted position when the collar is moved toward the wedge, said supporting members being proportioned so as to permit of a relatively wide range of adjustment and at the same time being substantially entirely concealed behind the plate when hung in place upon a wall.

9. A plate hanger for attachment to a plate for wall decoration and display comprising a main supporting member having provision at its upper end for attachment to the wall and provided at its lower end with forwardly extended, diverging

hook portions for engagement with the lower rim portion of the plate; an elongated supporting member having a forwardly extended hook portion at its upper end for engagement with the upper rim portion of the plate; a collar loosely embracing said supporting members, and a longitudinally disposed wedge interposed between said supporting members adapted to permit longitudinal adjustment of the parts when the collar is moved away from the wedge and to lock the parts in their adjusted position when the collar is moved toward the wedge, said main supporting member being less in length than the diameter of the plate to be supported and substantially equal in length to said elongated supporting member whereby to permit of a relatively wide range of adjustment of said members while at the same time enabling the same to be substantially entirely concealed behind the plate when hung in place upon a wall.

10. A plate hanger for attachment to a plate for wall decoration and display comprising a main supporting member of a relatively thin flexible material having provision at its upper end for attachment to the wall and provided at its lower end with forwardly extended, diverging hook portions for engagement with the lower rim portion of the plate; an elongated supporting member having a forwardly extended hook portion at its upper end for engagement with the upper rim portion of the plate, encircling means for re-

taining the members in assembled relation and to permit longitudinal adjustment of said elongated member; and means including a member interposed between said supporting members arranged to flex the same to effect frictional locking of the parts in their adjusted position when said encircling means is moved toward said interposed member, the contacting faces of said members being provided with roughened surfaces to provide efficient gripping areas.

11. A plate hanger for attachment to a plate for wall decoration and display comprising a main supporting member having provision at its upper end for attachment to the wall and provided at its lower end with forwardly extended, diverging hook portions for engagement with the lower rim portion of the plate, an elongated supporting member having a forwardly extended hook portion at its upper end for engagement with the upper rim portion of the plate, a collar loosely embracing said supporting members, and a longitudinally disposed wedge interposed between said supporting members adapted to permit longitudinal adjustment of the parts when the collar is moved away from the wedge and to lock the parts in their adjusted position when the collar is moved toward the wedge, the contacting faces of said members being provided with roughened surfaces to provide efficient gripping areas.

CHARLES RICHARDS.
